UNITED STATES PATENT OFFICE.

WILLARD J. SPENCER, OF WATERBURY, CONNECTICUT.

POWER AIR-PUMP.

No. 898,522.

Specification of Letters Patent. Patented Sept. 15, 1908.

Application filed November 25, 1907. Serial No. 403,702.

To all whom it may concern:

Be it known that I, WILLARD J. SPENCER, a citizen of the United States, residing at Waterbury, in the county of New Haven and State of Connecticut, have invented a new and useful Improvement in Power Air-Pumps; and I do hereby declare the following, when taken in connection with the accompanying drawings and the letters of reference marked thereon, to be a full, clear, and exact description of the same, and which said drawings constitute part of this specification, and represent, in—

Figure 1 a view in side elevation of my improved power air-pump shown with its drying wheel in engagement with the fly wheel of the motor as well as with the driven wheel of the pump, and therefore in readiness for utilizing the motor to inflate the tires of the car or producing air pressures for any other desired purpose. Fig. 2 a view of the pump partly in plan and partly in horizontal section. Fig. 3 a view of the pump in inside elevation, its driving wheel being in this case shown in its normal or retired position in which it is disengaged from the fly wheel of the motor, its driven-wheel being broken away to show the adjustable and swinging arms arranged concentric with the said wheel, and the frame being shown by broken lines in one of the oblique positions in which it may be applied to the frame of the car.

My invention relates to an improvement in power air-pumps for installation upon automobiles, for furnishing air under pressure for inflating their tires, for their gasoline tanks, whistles, etc., the object being to produce a simple, compact, durable and efficient pump constructed with particular reference to convenience of installation.

With these ends in view, my invention consists in a power air-pump having certain details of construction and combinations of parts as will be hereinafter described and pointed out in the claims.

In carrying out my invention I employ a driving-wheel 2 made of vulcanized fiber or other equivalent material and having a large central bearing-hole 3 adapting it to be loosely mounted upon a stud 4 in position to engage with the periphery of the driven wheel 5 of the pump. The said stud 4 passes transversely through the outer end of a swinging arm 6 extending beyond the periphery of the wheel 5 and radially arranged with respect to the said wheel so as to swing

on the axis thereof so that the swinging movement of the arm will never carry the wheel 2 away from the periphery of the wheel 4. At its upper end the arm 6 is provided with a sleeve 7 which is mounted upon the journal 8 of the wheel 4 as shown in Fig. 2, the turning of the sleeve 7 upon the journal 8 providing for the swinging of the arm 6 as described.

The wheel 2 is normally held out of engagement with the fly wheel 9 of the motor by means of a cam 10 at the inner end of a lever 11 hung upon a stud 12 in the lower end of a normally fixed but adjustable arm 13 radially arranged with respect to the driven wheel 4 and extending alongside of the arm 6, though not quite parallel therewith. Normally the cam 10 engages with the stud 4 and holds the wheel 2 away from the periphery of the fly wheel 9 against the tension of a spring 14 engaging with the stud and itself carried by the arm 13, the said cam and spring engaging with the opposite faces of the stud as clearly shown in Fig. 1. When the lever 11 is thrown into its retired position so as to clear the cam 10 from the stud 4, the spring 14 asserts itself to swing the arm 6 upward and lift the wheel 2 into engagement with the fly wheel 9 without, however, disengaging the wheel 2 from the driven wheel 4, the lateral play of the wheel 2 upon the stud 4 due to the enlarged bearing hole 3 enabling the wheel 2 to accommodate itself in position for engagement with the fly wheel 9, as well as with the driven wheel 4 which through the driving wheel 2 is thus driven by the fly wheel 9.

At its upper end the arm 13 is furnished with a sleeve 15 large enough to receive the sleeve 7 for which it forms a bearing. Under this construction both the swinging arm 6 and the normally fixed or adjustable arm 13 are arranged to turn upon an axis concentric with that of the driven wheel 4. The said sleeve 15 is mounted in the inner arm of a yoke 16 and held in place against rotation by a bearing cap 17 secured in the usual manner to the said arm by nuts 18 which are loosened to permit the arm 13 to be adjusted as may be required at the time of the initial installation of the pump upon the frame of the automobile or other vehicle.

The yoke 16 as shown is cast integral with the cylinder 19 which has offset from its inner side a lateral web 20 terminating in a base-plate 21 located at a right angle to the

web 20 and in the plane of the driven wheel 4, this web being provided with screw holes 22 for its attachment to the frame of a car or other vehicle. When the pump is installed 5 the base-plate 21 and wheel 4 will stand in a vertical plane. The said yoke 16, cylinder 19, web 20 and base-plate 21 are all cast by preference in one piece, and constitute, as it were, the frame of the pump, or, as may be 10 said, a cylinder-containing frame. The cylinder 19 is furnished with a piston 23 connected by a piston rod 24 to a crank 25 the inner journal 8 of which has already been referred to, and the outer journal 26 of which 15 has bearing in the outer arm of the yoke 16 in which it is held in place by an ordinary bearing cap 27. The cylinder 19 is furnished with a removable head 28 having a nipple 29 through which the air compressed in the 20 cylinder is conducted to the tires of the wheels or to any other point where it is to be used.

In installing my improved pump the base-plate 21 is first attached in a vertical position 25 to the frame of a car or vehicle with the frame of the pump in a horizontal position as shown by full lines in Fig. 3, or in an inclined or oblique position as indicated by broken lines in the said figure. The particular inclination 30 of the frame of the pump will be dictated by circumstances, and is not material, but in any event the base-plate 21 will stand in a vertical plane. The broken lines in Fig. 3 must be understood, therefore, to indicate 35 only one of the inclined positions which the frame of the pump may take. After the plate 21 has been secured in place the nuts 18 will be loosened to permit the adjustable arm 13 to be set in the position required to locate 40 the driving wheel 2 close to but just out of contact with the fly wheel 9. After the arm 13 has been so set the nuts 18 will be tightened so as to fix the arm in that position. In this way the arms 6 and 13 are shifted as may 45 be required with respect to the longitudinal axis of the pump frame considered as a casting.

By locating the driven-wheel and base-plate of my improved power air-pump in the 50 same plane I secure an amount of convenience in installing the pump upon the frames of motor cars heretofore unknown as the pump may be applied to the frame of almost any car without the use of an intermediate 55 bracket or corresponding part, whereas great difficulty is found in applying power air-pumps as heretofore constructed to the frames of motor cars and to many cars they can not be applied at all without the use of 60 some intermediate parts.

I claim:

1. In a power air-pump for installation upon automobiles, the combination with a frame comprising a cylinder and a base-plate fixed with relation to each other, of a driven 65 wheel carried by the said frame and located in the plane of the base plate, whereby, in the installation of the pump upon the frame of an automobile, the base-plate may be applied directly to the frame without the use of 70 a bracket or other intermediate part.

2. In a power air-pump, the combination with a frame comprising a cylinder and a base-plate, of a driven wheel carried by the 75 said frame and located in the plane of the 80 said base-plate, a swinging arm carried by the frame and having the same center as the said driven wheel, a driving-wheel carried by the said arm in position to engage with the said driven-wheel for driving the same, an 85 adjustable arm having the same center as the driven-wheel, and means carried by the adjustable arm for controlling the position of the driving-wheel carried by the swinging arm.

3. In a power air-pump, the combination with a frame comprising a cylinder and a base-plate, of a driven-wheel carried by the 90 said frame, a swinging arm mounted in the said frame concentric with the driven-wheel 95 and extending beyond the periphery thereof, a driving-wheel mounted in the outer end of the said swinging arm in position to engage with the driven-wheel, an adjustable arm extending alongside the swinging arm, and a cam-lever located in the outer end of the adjustable arm for controlling the location of the said driving-wheel with reference to the fly wheel of a motor.

4. In a power air pump, the combination 100 with a frame comprising a cylinder and a base-plate, a crank mounted in the said frame, a driven wheel secured to one of the journals of the said crank, an adjustable arm mounted in the said frame concentric with the 105 driven-wheel, a swinging arm also carried by the said frame and swinging on the axis of the said wheel, a driving-wheel mounted in the swinging arm, and means applied to the normally fixed adjustable arm for controlling 110 the position of the driving wheel with respect to the fly-wheel of a motor.

In testimony whereof, I have signed this specification in the presence of two subscribing witnesses.
